US0D1011318S

(12) **United States Design Patent** (10) **Patent No.:** **US D1,011,318 S**
(45) **Date of Patent:** **** Jan. 16, 2024**

(54) **MOTORCYCLE HELMET HEADSET**

(71) Applicant: **Shenzhen Asmax Infinite Technology Co., Ltd.**, Shenzhen (CN)

(72) Inventor: **Cheng Luo**, Shenzhen (CN)

(73) Assignee: **Shenzhen Asmax Infinite Technology Co., Ltd.**, Shenzhen (CN)

(**) Term: **15 Years**

(21) Appl. No.: **29/902,424**

(22) Filed: **Sep. 13, 2023**

(30) **Foreign Application Priority Data**

Sep. 1, 2023 (EM) 015032706-0001

(51) **LOC (14) Cl.** **14-01**

(52) **U.S. Cl.**

USPC **D14/223**; D14/206

(57) **CLAIM**

The ornamental design for a motorcycle helmet headset, as shown and described.

DESCRIPTION

FIG. 1 is a front, right and top perspective view of a motorcycle helmet headset, showing my design;

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the motorcycle helmet headset that form no part of the claimed design.

1 Claim, 8 Drawing Sheets
